UNITED STATES PATENT OFFICE.

HENRY M. VAUGHAN, OF NEWTON, IOWA.

VAPOR-BURNING STOVE.

SPECIFICATION forming part of Letters Patent No. 414,736, dated November 12, 1889.

Application filed July 5, 1887. Serial No. 243,309. (No model.)

To all whom it may concern:

Be it known that I, HENRY M. VAUGHAN, a citizen of the United States of America, and a resident of Newton, in the county of Jasper and State of Iowa, have invented an Improved Vapor-Burning Stove, of which the following is a specification.

My object is to prevent the dangers and accidents incident to the use of vapor-burning stoves, to improve the construction and operation of vapor burning stoves in which volatile fluids are carbureted by means of mechanism for forcing and mixing air with the hydrocarbon vapor before it is admitted to the burners, and also to provide a means for signaling to the attendant when the reservoir containing the fluid is nearly empty and a fresh supply of liquid fuel is required to continue the operation of the stove.

My invention consists in the construction and combination of a liquid-reservoir, a fan, and an automatic signal, as hereinafter set forth, in such a manner that all of these elements will be compactly united at the base portion of the stove and readily put in operation and continued in operation and controlled by a person of ordinary intelligence.

Figure 1 of the accompanying drawings is a vertical sectional view showing a fan and fan-operating mechanism combined with an air-tight reservoir. Fig. 2 is a sectional view and modification of Fig. 1, showing an automatic alarm combined with the fan-operating mechanism. Fig. 3 is a side view of a complete stove, and Fig. 4 a side view illustrating the construction and operation of the detent for operating the alarm mechanism at a stated time.

A is the top, and B the burners, of a stove of common form.

C represents a case in which a carburetor is inclosed and fixed to the stove.

d d are tubes extending from the burners B into the top of the reservoir to conduct carbureted air from the reservoir to the burners. Stop-valves d' are applied to burners or tubes to stop the passage of the carbureted air at pleasure.

F represents an air-tight reservoir that may vary in shape and size as desired.

G is a case for a fan and fan-operating mechanism, formed integral with the reservoir F, or fixed thereto in any suitable way.

G² is a partition in the case G, that produces a fan-chamber in which is located a fan H. It has an open bottom or openings at its lower portion, through which air is admitted.

H² is an open-ended tube extending from within the top of the fan-chamber into the top of the air-tight reservoir. For carbureting air with kerosene or other heavy oils this tube is made to terminate near the bottom of the reservoir.

J is a fan-shaft, and J² a driving-shaft connected therewith by means of gearing in such a manner that power and motion can be transmitted from the driving-shaft to the fan at pleasure by means of springs or other suitable motors, as required, to actuate the fan and to force air into the air-reservoir, to be carbureted therein from contact with volatile liquid in the reservoir. In Fig. 2 the driving-shaft J² is shown tubular, and a solid shaft k extends through, to be operated automatically as an alarm device when the driving-shaft has made a given number of revolutions and the liquid in the reservoir is nearly exhausted. The driving-shaft J² and the shaft k have square outer ends, upon which keys can be placed to rotate them independently, as required, to store power in the springs connected therewith.

l l are hammers fixed to the shaft k in such a manner that they will strike a bell m that is fixed inside of the fan-chamber.

n is a spring fixed to the shaft at one of its ends and to the case at its opposite end in such a manner that power can be stored in the spring by rotating the shaft by means of a key.

n' is a ratchet-wheel fixed to the shaft k.

o is a detent pivoted to the case in such a manner that it will in its normal condition by force of gravity engage the ratchet-wheel and lock the shaft.

p is a toothed wheel, and r is a cam on the end of its axle that will operate the detent at each complete revolution of the wheel, as required, to free the shaft k so it will rotate.

and make the hammers *l* strike the bell continuously until the force stored in the spring is exhausted.

s is a cam on the tubular driving-shaft *J*, 5 that engages the teeth of the wheel *p* successively, as required, to impart intermittent motion to the wheel, so that it will make a complete revolution in any given time desired, as required, to start the alarm when 10 the supply in the reservoir is nearly exhausted. As the oil-reservoir may vary in size, the capacity of the fan and the spring for operating it must also vary, as required, to correspond with the reservoir, so that 15 when the reservoir is filled and the spring wound up the number of revolutions of the driving-shaft will be proportioned to the time required to exhaust the reservoir, so that the alarm combined with the driving-shaft will 20 be operated before the reservoir becomes empty.

In the practical use of my carbureted-air stove, when gasoline or other volatile combustible fluid is placed in the reservoir, I 25 wind up the spring-motor and start the fan to force air through the fan-chamber into the air-tight reservoir, and then open one or more of the stop-valves in the tubes extending to the burners to allow the carbureted air to 30 escape and to be lighted with a match in the manner that common illuminating-gas is distributed and burned. Culinary vessels are then set over the burner in a common way and heat generated under them by means of the 35 carbureted air, and continued as long as required, or until the supply of the combustible liquid in the reservoir is exhausted.

I am aware that a hydrocarbon-chamber of peculiar construction and a chamber containing air-forcing mechanism have been attached 40

to a stove at different points and connected with each other and with burners by means of tubes; but my manner of constructing and combining a reservoir, a fan-chamber, a forcing mechanism and alarm mechanism with 45 a stove is novel and greatly advantageous in that the tube that conveys air from the fan to the reservoir and all the fan-operative mechanism is concealed and combined so that they can be jointly attached to a stove at 50 one point at the base to improve the appearance and efficiency of a hydrocarbon-stove. The automatic alarm mechanism is also concealed and advantageous in the combination in that it will give notice to an attendant before the oil is exhausted, so the reservoir can be again filled before the fire is extinguished and the cooking operations interrupted.

I claim as my invention—

1. The combination of a reservoir, a fan-chamber, a tube extending upward from the fan-chamber through the reservoir and terminating and concealed therein, a rotary fan, and mechanism for operating the fan with a 65 vapor-burning stove, in the manner and for the purposes stated.

2. The combination of a reservoir, a fan-chamber, a tube extending from the fan-chamber upward through the reservoir and terminating and concealed therein, a rotary fan, mechanism for operating the fan, and an automatic signaling or alarm mechanism with a vapor-burning stove, to operate in the manner set forth, for the purposes stated.

HENRY M. VAUGHAN.
